(57) **CLAIM**

The ornamental design for a photo frame, as shown and described.

DESCRIPTION

FIG. 1 is a top perspective view of a photo frame with a closed hinged portion, partially rotated, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view of FIG. 1 in an alternate state, with a closed hinged portion, fully rotated; and,

FIG. 10 is a top perspective view of FIG. 1 in a second alternate state, with the hinged portion partially rotated and open, shown with a sliding panel partly extended through a slot feature.

The broken lines in the drawings illustrate the portions of the photo frame, which form no part of the claimed design.
